UNITED STATES PATENT OFFICE

167,812

TEXTILE FABRIC

Daniel Scher, Brooklyn, N. Y., assignor to Decorative Textiles, Inc., Pawtucket, R. I., a corporation of Rhode Island

Application March 14, 1952, Serial No. 18,881

Term of patent 14 years

(Cl. D92—1)

To all whom it may concern:

Be it known that I, Daniel Scher, a citizen of the United States, residing at Brooklyn, in the county of Kings, city of New York, and State of New York, have invented a new, original, and ornamental Design for a Textile Fabric, of which the following is a specification, reference being had to the accompanying drawing, forming a part hereof.

The figure represents a plan view of the design of my new textile fabric.

I claim:

The ornamental design for a textile fabric, as shown and described.

DANIEL SCHER.
